Primary Examiner — Anhdao Doan(74) *Attorney, Agent, or Firm* — Marshall, Gerstein & Borun LLP(57) **CLAIM**

The ornamental design for a health measurement device, as shown and described.

DESCRIPTION

FIG. 1 is a front perspective view showing a new design for a health measurement device;

FIG. 2 is a front view of the health measurement device of FIG. 1;

FIG. 3 is a rear view of the health measurement device of FIG. 1;

FIG. 4 is a left side view of the health measurement device of FIG. 1;

FIG. 5 is a right side view of the health measurement device of FIG. 1;

FIG. 6 is a top plan view of the health measurement device of FIG. 1; and,

FIG. 7 is a bottom plan view of the health measurement device of FIG. 1.

The elliptical shapes seen in FIG. 7 are surface ornamentation with no appreciable depth element.
